Patented June 13, 1922.

FIG. 1.

FIG. 2.

Eugene Gase

UNITED STATES PATENT OFFICE.

EUGENE GASE, OF SAGINAW, MICHIGAN, ASSIGNEE TO BAKER-PERKINS MANUFACTURING CORPORATION, OF SAGINAW, MICHIGAN.

GATE CONTROL FOR FLOUR BINS.

1,419,556.

Specification of Letters Patent. Patented June 13, 1922.

Application filed September 27, 1920. Serial No. 413,216.

To all whom it may concern:

Be it known that I, EUGENE GASE, a citizen of the United States, residing at Saginaw, in the county of Saginaw and State of Michigan, have invented new and useful improvements in Gate Controls for Flour Bins, of which the following is a specification.

This invention relates to improvements in devices for operating from a distance the shutters of the gate valves of a number of bins containing flour, grain or similar materials and has for its object to make the manipulation of these shutters easy, correct and quick, and especially also to prevent any possible mistakes by causing open shutters to close automatically as soon as a fresh one is opened.

For this purpose, I provide each end of the shutters sliding in the gate valves used in the series with a wire, chain or other flexible, but inelastic means (hereafter in general called "wire"), and connect the wire at one end of each shutter to a heavy weight,

spring or other elastic means adapted to keep the valve closed as its normal condition, and the wire at the opposite end of each shutter to the shorter part of a two armed lever adapted to overcome the resistance of the spring or the like and thus to open the valve, provided all the wires are tightly stretched in the normal position of the valve being closed. The levers, of which as many are employed as there are gates to be operated,

have the same length and fulcrum, turn round a preferably horizontal shaft common to all and fixed to the side walls of a boxlike support containing the whole lever arrangement, and are provided at the ends of their upper and usually longer arms with suitable handles to work the same; the ends of their lower and usually shorter arms, to which the wires are fastened, are shaped in such a manner that they catch easily into the notches of

counterweighted pawls—one for each lever—fixed to a common shaft rotatably mounted in the support for the levers and preferably parallel to the shaft round which the latter turn. The levers and pawls are so arranged to each other that, when, in order to open a gate, a lever is turned so as to draw its shutter open against the pressure of the weight, spring or the like keeping it normally closed, this lever will press down the tip of its pawl, until it catches into the notch of the

latter, and release automatically at the same time any other lever or levers held by their pawls, whereby the shutters belonging to these levers are drawn back into the closed position. I preferably use springs to keep the shutters closed, and, as the openings of the latter have usually a greater length than the way to which the springs may be drawn out with ease and safety, and also than the extent of the movement of those points of the levers to which the wires operating them are attached, I fix wires of a suitable length to each end of the shutters, lead them over sheaves rotatably mounted in loose forklike frames, and fasten the other ends of these wires to stationary hooks or similar supports; the stem of one fork is then fixed to the loose end of the spring, and that of the opposite one to the wire leading to the lever. This arrangement has the lengthening effect of a tackle and facilitates at the same time the working of the device.

The accompanying drawings serve for more minutely describing and explaining by way of example the essential constructional parts of my invention; they represent the apparatus which I use for operating the gate valves arranged in the passages leading flour from a screw conveyer into the top of large bins, placed, as is usual in large bakeries, in a row side by side on the floor above a battery of kneading machines.

Fig. 1 is a top view of four flour bins with their gate valves and the devices and wires to work them. Fig. 2 shows the arrangement of the four levers for operating the valves, and Fig. 3 is a cross section on line 3—3 of Fig. 2, showing a lever in the position, when the gate is open, in dark lines, and, when the latter is closed, in dotted lines.

Like numerals of reference denote corresponding parts serving the same or a similar purpose.

In Fig. 1 the four flour bins are indicated by the numerals 1, 2, 3 and 4; they are fed by the screw conveyer 5 and connected to and disconnected from the latter by the gate valves 6, 7, 8 and 9 respectively. Each valve has a shutter 10 with an opening 11 therein for making the connection between the conveyer 5 and the bin, to which the valve belongs. That end of each shutter 10, to which the opening 11 is nearest,—the back end—is provided with a hook 12, to which one end of the wire 13 is connected, while the other

2

end of 13 is attached to the hook 14 fixed to a side wall of the conveyer 5. The wire 13 runs over the loose sheave 15 freely revolving in its fork 16 connected by its stem to the free end of the strong spring 17, the other end of which is rigidly fixed to the top of the bin. The spring 17 must be of such a strength and the wire 13 of such a length and so tightly stretched that by the 10 action of the spring 17 the shutter 10 remains normally closed and can only be drawn open by a force applied to the front end of 10 and sufficiently great to overcome the effect of the spring. The opposite end 15 of the shutter 10—the front end—is fitted with the hook 18 to which one end of the wire 19 is attached, while the other end of the latter is connected to the hook 20 fixed to a side wall of the conveyer 5; the wire 19 20 runs over the loose sheave 21 freely revolving in its fork 22. The stem of the latter is connected to the wire 23 passing over the stationary guide pulleys 24 and the like to the lever working the shutter 10.

25 Four separate levers 25, 26, 27 and 28 are provided for manipulating the shutters 10 of the gate valves 6, 7, 8 and 9 respectively; all the four levers have the same fulcrum 29 and turn loosely round the shaft 30 fixed 30 to the sides of the boxlike support 31, in which the lever arrangement is housed. The upper and longer arms of these levers, protruding through slits 32 provided in the top of the box 31 and as long as the stroke of the 35 corresponding levers require, end in serviceable handles 33 marked with the number of the bin, the gate of which they are intended to work, (1, 2, 3 and 4 corresponding to the bins 1, 2, 3 and 4). The lower and shorter arms of the levers are completely contained 40 within the box 31 and furnished with hooks 34 to which the wires 23 are connected after passing over the guide pulley 35, rotatably supported in the forklike bracket 36 fixed to 45 the back of the box 31, and the guide pulley 37, rotatably mounted in the forklike bracket 38 attached to the front of 31. Slits 39 of a length to give ample play for the movement of that part of the wires 23 extending 50 between the hook 34 and the guide pulley 37 are cut in the front wall of the box 31, and openings 40 are provided in the front wall, and similar ones 41 in the back wall of 31, for those parts of the wires 23 55 extending between the pulleys 37 and 35 to pass through. The ends of the lower arms of the levers are shaped so as to easily catch into the notches or indents of shoe-shaped pawls 42, four of which—one for each lever 60 —are fixed rigidly and in line to the shaft 43 revolvably mounted in bearings arranged in the side walls of the box 31; thus, when one lever acts upon the pawl belonging thereto, the three other pawls will simultaneously 65 perform exactly the same movement as that

acted upon does. Each pawl 42 consists of the broad, curved front piece 44, its convex surface pointing upwards and towards the front wall of 31, of the main part 45 extending the whole length of 42 and forming 70 with the back of the tip 44 the notch 46 into which the lever, when drawn forward, catches, and of the heel-like back part 47 heavier than and acting as counterweight 75 for the front piece 44. The shaft 43 is fixed by suitable means as screws to the main part 45 of the pawls 42 at about their middle and usually parallel to the shaft 30 round which the levers are turned. All the pawls are 80 preferably of the same shape and size, and the lower arms of the levers equal in length. In order to prevent the pawls from dropping in consequence of their heavy back parts 47 beyond the active zone of the levers, a rod 48 is fixed at a suitable distance underneath these back parts to the sides of the box 31. The wires 19 and 23, by means of which the levers actuate the shutters 10 of the valves, must be of such a length and so tightly stretched that the springs 17, 90 which retain the shutters in their closed position, draw the lower ends of the levers, when free and released from their pawls, against the front wall of the box 31, as shown in dotted lines in Fig. 3 for the lever 95 27. The wires 13 and 19 with their sheaves 15 and 21 respectively form tackles and serve to make the manipulation of the levers easier and to prolong the way, to which the springs 17 are drawn out by the latter, to 100 the considerably greater length to which the shutters must be pulled forward in order to place the openings 11 in their entirety into the proper position for fully connecting the 105 conveyer with the bins.

The levers, their pawls and the shafts belonging to them are so arranged to each other, that, when, for opening a gate valve, the lever belonging thereto is drawn forward, it presses down the tip of the pawl 110 42, gliding along its curved part 44, until it catches into the notch 46, whereupon the front part 44 is moved upwards again by the weight of the heavier back part 47 and thus the lever is locked in this position; as 115 all the other pawls move simultaneously with that acted upon by the lever, any other lever or levers held locked by their pawls will be released and the gate valves belonging thereto shut. It follows that, 120 provided a single lever is operated at a time for opening its valve all the other gate valves will be closed, if they are not yet in this position; and that it is thus impossible to make the mistake of leaving a 125 valve, which is not to be used any longer, unclosed, and very difficult indeed to open a wrong valve, though the bins and their valves are invisible to and separated from the attendant by ceilings and walls.

I claim:

1. In apparatus of the kind described, the combination with a plurality of bins, of gate valves, one for each bin, of movable shutters for opening and closing the said valves, of resilient means connected to one end of the said shutters and so adapted as to keep the said valves normally closed, of flexible, but inelastic means attached to the opposite end of the said shutters, of a stationary support, of a shaft rigidly affixed in the latter, of levers, one for each of the said valves, each lever turning round the said shaft and connected at such a point to one of the said flexible, but inelastic means, that, when the said lever is turned, the resistance of the said resilient means, keeping the valve belonging thereto shut, is overcome, and the latter is opened, of a shaft rotatably mounted in the said support, of counter-weighted pawls corresponding to the said levers, rigidly affixed to the last named shaft and provided with notches, the said levers, the said pawls and their notches being so arranged that, when any one of the said levers is turned, it catches in the notch of the corresponding pawl, as soon as the corresponding gate valve has been completely opened, and is locked in this position by the heavier parts of all the said pawls dropping, and of curved surfaces, one arranged at each of the latter in front of its notch in such a manner that, when anyone of the levers is turned for opening its corresponding gate valve and slides along such surface, the heavier parts of all the said pawls are lifted, whereby any other of the said levers retained in the notch of its pawl is released therefrom and the corresponding gate valve closed.
2. In apparatus of the kind described, the combination with a plurality of bins, of gate valves, one for each bin, of movable shutters for opening and closing the said valves, of resilient means connected to one end of the said shutters and so adapted as to keep the said valves normally closed, of flexible, but inelastic means attached to the opposite end of the said shutters, of two-armed levers—one for each of the said gate valves—having the same fulcrum, their shorter, equally long arms being connected to the said flexible, but inelastic means, and their longer arms being provided with handles for working the same, of a stationary shaft serving as fulcrum for all the said levers, of a support in which the said shaft is rigidly mounted, of pawls, one for each of the said levers, each pawl consisting of a lighter frontpart, a heavier backpart and a supported middlepart provided with a notch, of a shaft rotatably mounted in the said support of and parallel to the said stationary shaft and carrying all the said pawls rigidly affixed thereto at a point of their middlepart, the lighter frontparts of the same pointing towards the shorter ends of the said levers, the latter, the said pawls and their notches being so arranged, that, when anyone of the said levers is turned, it catches in the notch of the corresponding pawl, as soon as the corresponding gate valve has been completely opened, and is locked in this position by the weight of the heavier backparts of all the said pawls dropping, and of curved surfaces, one arranged at the lighter frontpart of each of the said pawls, starting at the notches contained in their middlepart in such a manner, that, when anyone of the said levers is turned for opening the corresponding gate valve, it lifts, sliding along the said surface, the heavier backparts of all the said pawls, whereby any other of the said levers, retained in the notch of its pawl, is released therefrom and the corresponding gate valve closed.
3. In apparatus of the kind described, the combination with a plurality of bins, of gate valves, one for each bin, of movable shutters for opening and closing the said valves, of wires, two connected to each of the said shutters, one at one side for opening and one at the opposite side for keeping the said valves closed, and fastened with their other ends to stationary supports, of loose sheaves over which the said wires are tightly stretched, of forks in which the said sheaves are rotatably mounted, of springs attached to those of the said forks situated at one side of the said shutters and adapted to keep them normally closed, and of wires attached to those of the said forks placed at the opposite side of the said shutters and tightly stretched and connected with their other ends to levers adapted and arranged to draw the said shutters open.
4. In apparatus of the kind described, the combination with a plurality of bins, of gate valves, one for each bin, of shutters sliding in the said valves, of wires, two connected to each of the said shutters, one at one side for opening and one at the opposite side for closing the said valves, and fastened with their other ends to stationary supports, of loose sheaves over which the said wires are tightly stretched, of forks in which the said sheaves are rotatably mounted, of springs attached to those of the said forks situated at one side of the said shutters, and adapted to keep them normally closed, of wires attached to those of the said forks placed at the opposite side of the said shutters, of levers—one for each of the latter—connected to the last named wires, tightly stretched, in such a manner that, when such a lever is turned, the corresponding gate valve is opened, of a stationary shaft round which all the said

levers are turned, of a support in which this shaft is rigidly fixed, of a shaft rotatably mounted in the said support, of pawls corresponding to the said levers, rigidly affixed to the last named shaft and provided with notches for the said levers to catch and be locked in, after the latter have been turned so far that the corresponding gate valves are quite open, and of curved sur-

faces, one arranged at each of the said pawls 10 in front of its notch in such a manner that, when anyone of the said levers is turned for opening its corresponding gate valve and slides along such surface, it unlocks and releases any other of the said levers re- 15 tained in the notch of its pawl, whereby the corresponding gate valve is closed.

EUGENE GASE.
